UNITED STATES PATENT OFFICE.

ARTHUR H. WESTON, OF BALTIMORE, MARYLAND, ASSIGNOR TO THE T. H. SYMINGTON COMPANY, OF BALTIMORE, MARYLAND, A CORPORATION OF MAINE.

UNDERFRAME-REINFORCEMENT.

1,234,987.

Specification of Letters Patent. Patented July 31, 1917.

Application filed December 18, 1914. Serial No. 877,342.

To all whom it may concern:

Be it known that I, ARTHUR H. WESTON, a citizen of the United States of America, residing in the city of Baltimore, State of Maryland, have invented certain new and useful Improvements in Underframe-Reinforcement, of which the following is a specification.

Owing to the continually increasing weight and power of the freight locomotives in use and the consequent increase in the length of freight trains and therefore of the intensity of the drawing and buffering stresses applied to the cars, the old wooden underframes are rapidly becoming obsolete because they are insufficient to meet the demands placed upon them by the new conditions. More particularly, the bolts which hold the cheek plates pull out of the wood causing failure by splitting of the sills around the bolt holes and keys; also the fact that the draft sills are placed below the center sills causes a downward bending moment to be applied to these sills in buffering which is frequently in excess of the transverse strength of the sills so that they break downward over the bolster.

Failure of the underframe in all of these and other forms leads to breaking of trains and derailments resulting in frequent wrecks with the usual property damage and loss of life. These conditions are now generally recognized and have resulted in the demand for new equipment. However, in many instances the expense involved is prohibitive.

To meet the difficulties thus presented, the applicant has evolved a center sill reinforcement by means of which the old cars are rendered fit for use. This includes metal draft plates to take the place of the old wooden draft sills and continuous metal beams extending along the sills whereby the draft plates at the front and rear of the car are supported and preferably tied together. The draft plates each have a depending portion extending below the sills. This forms a seat for the corresponding cheek plate, and the draft plates provided have this seat shaped to coöperate with the original cheek plates used on the wooden frame. Most of these old cheek plates have lugs to be set into the wood and the draft timbers in cars so equipped are recessed to receive these lugs, so that the old cheek plates can be used in the reinforced structure. By use of these

metal members, pulling out of the bolts, splitting at the keys and failure from similar causes are prevented and the whole structure is reinforced in front of and in the vicinity of the bolster so that breaking down at this point is prevented. A laterally extending horizontal web is also provided in the vicinity of the bolster, sufficient to resist the lateral stresses applied to the sills.

In the accompanying drawings I have shown so much of a wooden underframe reinforced in accordance with my invention in its preferred form, as is necessary to its illustration.

Figure 1 is a longitudinal section view of the central portion of the car underframe showing the wooden center sill reinforced by a metallic draft plate, portions of the underframe being shown in section.

Fig. 2 is a side elevation of the draft plate.

Fig. 3 is a longitudinal section through the lower portion of the draft plate showing a cheek plate assembled therewith, and

Fig. 4 is a cross section on the line 4—4 of Fig. 1.

Referring to the drawings by numerals, the wooden center sills 1 extend from end to end of the car and are reinforced by members which may be in the form of channel irons 2 secured to the inner faces of the sills by means of bolts 3. In the form of the invention shown, these channels terminate at the front and rear near the rear ends of the cheek plates, though they may extend forward to the end sills.

Secured to the channels 2 at each end and also to the inner faces of the center sills, I provide draft plates 4. These are fastened to the wooden sills by means of long bolts 5 and to the channels by rivets 6 and the bolts 3, the latter passing through the channels, the draft plates and the wooden sills. In the instance illustrated, to avoid cutting the wooden sills, the channels are sprung slightly at 8 so as to cause them to overlie the plates 4 which, instead of being set into the sills as shown, are laid on the inner faces of the sills. To give sufficient space to accommodate the draft gear made of standard width to fit between the sills, the plates are shown as offset at 9, see Fig. 4, at the lower edges of the sills bringing the inner faces of the lower or depending portions of the plates 10 into the same vertical 11.

plane as the outer faces 11, *i. e.*, those which are disposed toward the sills; and the top portions of the plates. The lower edges of the plates in the form of the invention shown, are turned outward at 12 to form a stiffening member and the front ends are connected to the end sill by means of vertical angles 13 each having one flange secured to the corresponding draft plate and the other flange bolted to the timber, as shown, by means of bolts 14.

At the rear the draft plate is cut away at the bottom to the height of the bolster, giving a vertical edge 15 which is secured to the bolster by means of a vertical angle 16 having one flange riveted to the central web of the bolster at 17 and the other edge to the plate. The upper portion of the plate extends well to the rear of the bolster along the surface of the center sill, the flat face being covered by the channel as previously described, and the entire portion of the plate which is overlapped by the channel, is secured to the channel by means of rivets 6 and bolts 3, as described.

The draft plate 4 is reinforced centrally, or rather the top edge of the depending portion of the draft plate is secured to the sills by means of a horizontal angle iron 18 having one flange, which is vertical, secured to the outer face of the plate along the upper edge of the depending portion, and the other flange, which is horizontal, secured to the bottom surface of the sill.

The lower portion of the draft plate 4 is provided with a plurality of recesses 19 and 20 which are adapted to receive the correspondingly formed lugs or projections 21 and 22 formed on the rear face of the cheek plates or stop castings 23. In wooden car construction it is customary to provide gains

or rabbets in the wooden sills in order to receive the projecting lugs 21 and 22, and it is necessary to provide these recesses with metal draft plates to receive these forces in order to permit the use of the old cheek plates with the new car construction. 45

Thus the sills are reinforced throughout their entire length, the draft plates which support the cheek plates at the front and rear, tied together and secured to the bolster and the end sill, and the whole structure is abundantly reinforced at the bolster to prevent breaking down at this point, as well as to eliminate the possibility of lateral yielding. 50 It is of course understood that many of the details described are not essential and may be omitted.

I have thus described my invention in its preferred form specifically and in detail in order that its nature and operation may be clearly understood. However, the specific terms herein are used in their descriptive rather than in their limiting sense and the scope of the invention is defined in the 65 claim:

In combination with cheek plates provided with projecting lugs or bosses on the outer faces thereof, wooden center sills; metal draft plates connected to the inner faces of the said sills adjacent the outer ends thereof and depending below the same, the depending portions of said draft plates being provided on their adjacent faces with recesses adapted to receive the projecting 75 lugs on the cheek plates.

Signed by me at Baltimore, Maryland, this 14th day of December, 1914.

ARTHUR H. WESTON.
